MILL WITH GRINDING-RING.

1,187,246.

Specification of Letters Patent. Patented June 13, 1916.

Application filed December 4, 1914. Serial No. 875,515.

To all whom it may concern:

Be it known that I, EMILE BOUVIER, a citizen of the Republic of Switzerland, residing at Niederuzwil, Switzerland, have invented 5 new and useful Improvements in Mills with Grinding-Rings; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 Mills with grinding rings are known wherein the material is ground by rolls or cylinders pressed to the inner surface of a grinding ring by means of springs or through the medium of the centrifugal 20 force.

During the passing of the material under a cylinder the latter moves away from the grinding ring an amount in accordance to the size of the grains and in accordance to 25 the resistance opposing the grinding. Due to the great mass formed by the cylinder (break or guiding roll), its shaft bearing and lever linked thereto, the initial force for the removing of said cylinder from the 30 grinding ring is very great, because not only the tension of the spring, but also the inertia of the mass has to be overcome, but the kinetic energy given to the mass will be of influence proportional to the moving of 35 said cylinder and will counteract the tension of the spring. The material having passed the cylinder, the latter is brought back by the spring and will strike or pound with force against the grinding ring due to the 40 kinetic energy imparted to said cylinder. Thus by these known mills a large number of strokes occur due to the great mass of the parts moving during the grinding, these strokes being identical with loss of energy. 45 By other forms of construction of such mills one of the grinding rolls or cylinders has a steady bearing, the two other bearings being movable and in other cases the pressing springs are replaced by the centrifugal 50 force.

The object of the present invention is to eliminate the pounding by avoiding the moving of great masses. This is obtained by providing a flexible grinding ring and at 55 least three grinding rolls or cylinders which

rest against and operate to support the grinding ring, whereby the grinding of the material takes place between the cylinders and the grinding ring in consequence of the flexibility. The grinding rolls or cylinders 60 may rest against the outer surface or against the inner surface of the grinding ring; more than three grinding rolls and more than one grinding ring may be provided.

65 In the accompanying drawings, Figure 1 is a vertical cross section of one form of mill embodying my invention. Fig. 2 is a vertical cross section of a second form of construction. Fig. 3 is a section on A—A of Fig. 2, and Fig. 4 is the section of a third form of construction.

70 In Fig. 1 three cylindrical grinding rolls 11, 12, and 13 are rotatable in bearings (not shown) and arranged within and resting 75 against the inner surface of the grinding ring 14. Contrary to the above mentioned mills of known construction according to the present invention, the grinding ring 14 is resilient, yielding under a predetermined 80 pressure, that is it is deforming. The resilient grinding ring 14 is rotated by the friction of the rolls 11, 12, and 13 of which only one, or two, or all three, may be driven by belt pulleys. The material is fed from a 85 hopper 15 into the mill and comes successively between the grinding rolls 11, 12 and 13, and the grinding ring 14 and escapes sidewise after it has been ground.

90 In the form of construction shown in Figs. 2 and 3, the cylindrical grinding rolls 16, 17, and 18 rest against the outside of the resilient grinding ring 19 and are rotatable in bearings (not shown). Here the ring 19 is also rotated by the friction of the grinding rolls, only one, or two, or all three of them may be driven by belt pulleys 20 as shown in Fig. 3.

95 The material fed from a hopper 21, comes first between ring 19 and roll 16, and then between ring 19 and roll 17. By arranging the blade 22 either in the position indicated by dot and dash-lines or in the position indicated in full lines (Fig. 2) the ground material can either be led directly toward 100 the outlet of the mill or onto a beater 23 formed of wings fixed on a rotating shaft, said wings throwing the larger particles of the material or grains upward between the grinding roll 18 and the grinding ring 19. 105 110 115 120 125 130

In the hereinbefore described forms of the mill, the particles of the material come between the grinding rolls and the grinding ring and the latter undergoes deformation and in consequence thereof presses onto the particles of material to be comminuted, said pressing stress increasing with the deformation of the ring. The larger the particles of material, the greater the pressure exercised by the grinding ring on these particles. The amount of the pressure, corresponding to a certain deformation of the form of the grinding ring is thus determined by the size of the particles of the material to be ground and also by the resistance of these particles to the comminuting.

The only mass working during the grinding is that, corresponding to the weight of the deformed part of the grinding ring. 20 The grinding takes place without pounding, that is, the grinding is obtained with a minimum of effort. If rounded off grains are to be obtained, one of the grinding rolls may be driven with a speed different from that of 25 one of the other grinding rolls.

The angular velocity of all grinding rolls may be equal. Instead of only a single grinding ring more of such rings may be arranged next to one another, for instance 30 three rings, as shown in Fig. 3; this can also be the case in the mill shown in Fig. 1. These rings can therefore have an equal or a different resiliency and may be driven by common grinding rolls (Fig. 3).

35 Corresponding to the diameter of the grinding ring a more or less greater number of grinding rolls may be used. The minimum however is three.

The peripheral plane of the grinding 40 rollers can also have another form than a cylindrical one. In Fig. 4 the peripheral plane of the grinding ring or rings 24 have a concave profile and the grinding roll or rolls 25 have a corresponding convex profile. 45 The working of a mill thus constructed is the same as the working of the hereinbefore described forms of construction.

I claim—

1. In a grinding mill, three rotatable 50 grinding rolls in fixed relative position, and a resilient grinding ring in frictional engagement with said rolls.

2. In a grinding mill, three rotatable grinding rolls in fixed relative position, a resilient grinding ring in frictional engagement with said rolls, and supported solely by the latter. 55

3. In a grinding mill, three rotatable grinding rolls in fixed relative position, a resilient grinding ring in frictional engagement with said rolls, supported solely by the latter, and means to positively drive one of said rolls. 60

4. In a grinding mill, three rotatable grinding rolls in fixed relative position, a resilient grinding ring in frictional engagement with said rolls, supported solely by the latter, and means to positively drive two of said rolls. 65

5. In a grinding mill, a plurality of rotatable grinding rolls in fixed relative position, and a resilient grinding ring in external contact with said rolls and supported solely by the latter. 70

6. In a grinding mill, three rotatable 75 grinding rolls in fixed relative position, and a resilient grinding ring in external contact with said rolls and supported solely by the latter.

7. In a grinding mill, a resilient grinding 80 ring, three rotatable grinding rolls in fixed relative position uniformly distributed around and in contact with the external periphery of the ring.

8. In a grinding mill, a resilient grinding 85 ring, three rotatable grinding rolls in fixed relative position uniformly distributed around and in contact with the external periphery of the ring, and means to positively drive one or more of said rolls. 90

9. In a grinding mill, a plurality of resilient grinding rings having a common axis, three rotatable grinding rolls in fixed relative position uniformly distributed around and in frictional engagement with the external peripheries of said rings, and means to rotate one of said rolls. 95

In testimony that I claim the foregoing as my invention, I have signed my name in presence of two subscribing witnesses.

EMILE BOUVIER.
